UNITED STATES PATENT OFFICE.

CHARLES I. HOAG, OF CHICAGO, ILLINOIS.

OIL BURNER.

Application filed June 1, 1925. Serial No. 34,017.

My invention pertains to an oil burner, and the main object is to provide an efficient and durable burner of this kind which is very economical to manufacture, and is also very economical in use. Another object is to provide such a burner having a rotatable tubular member with means for taking in air and for spreading oil and thoroughly mingling the air with the oil so as to fully vaporize or 10 gasify the fuel as it is being transmitted for use in the burner.

Other objects will appear hereinafter.

The invention consists in the combinations and arrangements of parts hereinafter described and claimed.

The invention will be best understood by reference to the accompanying drawings forming a part of this specification, and in which,

20 Fig. 1 is a vertical sectional view of one form of construction illustrating my invention;

Fig. 2 is a partial plan view thereof;

25 Fig. 3 is a horizontal sectional view taken on line 3—3 of Fig. 1;

Fig. 4 is a horizontal sectional view taken on line 4—4 of Fig. 1; and

30 Fig. 5 is an elevational view of the air supplying conduit showing the wing or lip thereon for forcing air into the conduit.

The form of construction illustrated comprising a base or platform 10 adapted to be supported on the floor and having a rib 11 to be imbedded in the cement or material of the floor so as to hold the base and burner firmly in position. A casting or housing 12 is mounted on the base 10, as with bolts 13, and is provided with a chamber or space 14 which forms a housing for the gearing and is adapted to be filled with lubricating oil by means of the supply pipe 15. The upper end of the casting 12 is dished to provide a safety bowl or dish 16 for receiving any over-flow or surplus oil from the burner, and an overflow pipe 17 extends from said bowl or dish. A tubular member or casing 18 is mounted on ribs 19 extending upwardly from bowl 16, and is provided with a funnel shaped portion 20 at its upper end for directing air outwardly which passes through said casing 18, and upwardly extending reinforcing ribs 21 are provided at its upper end.

35 A tube 22 for supplying oil is threaded in the base 10 and an oil opening or intake 23 connects said tube with the intake pipe 24.

The supply tube 22 has a cap or dome shaped member 25 threaded on its upper end, said member 25 being provided with downwardly extending discharge pipes 26 and with a 60 curved chamber 27 which directs the oil downwardly from tube 22 to pipes 26, as best indicated in Fig. 1. A closing element or plug 28 is removably mounted in the top of cap 25, providing access to chamber 27 and 65 to tube 22. This cap 25 is held snugly in position by the upper portions of ribs 21.

A cylindrical member 29 is adjustably mounted in casting 12, as with a set screw 30 or the like, and extends centrally upwardly from bowl 16. An air supplying conduit 31 is mounted on the upper end of member 29, preferably by means of an antifrictional bearing having a stationary portion 32 fastened on member 29, and rotary portion 33 75 mounted with a plug 34 in the lower part of conduit 31. A lock nut 35 is preferably used to lock plug 34 on a tubular member 36 which incloses oil tube 22 and has a pinion 37 mounted on its lower end, said pinion being provided with a sleeve 37' operating in an antifriction bearing 38. A bevelled gear 39 engages pinion 37 and is fastened with its sleeve portion 40 on a shaft 41, as with a set screw 42, said shaft operating in a bushing 43 mounted in casting 12, a bore 44 being provided for supplying oil to bushing 43 and shaft 41. A suitable motor 45 is mounted on base 10 and operates said shaft 41 and gear 39, as by means of a sleeve 46 and a washer 47 bolted to a companion sleeve 48 which is keyed to the motor shaft 45 as shown.

The air supplying conduit 31, is provided with a funnel shaped member 49 at its upper end to spread the oil or fuel from supply pipes 26 outwardly and upwardly during the rotation of said conduit and member, and said member 49 due to its funnel shape and the arrangement of the pipes 26 and the upper end 31' of conduit 31, also thoroughly mixes the air, coming from said conduit, into the oil spread and distributed by said member 49. A slit 50 is cut at a slant in the side of conduit 31, providing a 95 lip or wing 51 which is curved outwardly to such an extent and at such an angle as to take in and supply a suitable amount of air from member 18 into conduit 31, so that the oil, while it is being spread and distributed by the funnel 49 will be fully vaporized 100 and gasified, and the cap or dome 25 is ex-

tended slightly beyond funnel 45 so as to direct the air and fuel mixture radially outwardly toward the walls of the furnace in which the burner is installed. This cap is of sufficiently thick metal so as to retain heat and add in superheating the sheet of fuel and air issuing between it and the funnel 49. A sleeve 52 is provided on the upper end of the cylindrical member 29 and is arranged to retain sufficient oil or lubricant for the antifriction bearing means at the lower end of conduit 31, a pipe 53 being preferably also provided for feeding oil, as by gravity, to said bearing.

This burner is mounted within the grate 54, so as to have the top of the casing 18 and the top of the funnel member 49 extending above the grate, and material, such as cement or the like, is preferably placed around casing 18 and its top 20 and on the grate so as to have the air passing through casing 18.

In a burner constructed in accordance with my invention as disclosed above, the lip 51 is set or bent outwardly and regulated to receive and force into conduit 31 exactly enough air to be mingled with the fuel oil issuing from pipes 26, which oil is partly vaporized through the action of funnel 49 and thereupon is thoroughly commingled with the incoming air from said conduit 31, so that the air will serve as a carrier of the vapor distributed and spread from the top of the funnel shaped member 49 to the fire pot for combustion. The cap or dome 25 preheats this fuel mixture, and in cooperation with the rotating funnel 49 issues said fuel mixture radially outwardly. The supporting housing 12 also presents a great advantage by providing a lubricant chamber for the smooth and noiseless operation of gears 37 and 39 and the means on which they rotate.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. An oil burner comprising a vertical ro-

tatable air conduit open at the top, there being an opening in one side of said conduit and an outwardly extending vane to force air into and upwardly through said conduit; an oil vessel mounted on the upper end of said conduit; and means for introducing oil into said vessel, substantially as described.

2. An oil burner comprising a vertical rotatable air conduit open at the top, there being an opening in one side of said conduit and an outwardly extending vane to force air into and upwardly through said conduit; an oil vessel secured to said conduit adjacent the top thereof, said vessel having upwardly and outwardly flaring walls; and means for introducing oil into said vessel, substantially as described.

3. An oil burner comprising a vertical rotatable air conduit open at the top, there being an opening in one side of said conduit and an outwardly extending vane to force air into and upwardly through said conduit; an oil vessel mounted on the upper end of said conduit; means for introducing oil into said vessel; and a spreader head arranged above said oil vessel and extending laterally beyond the edges thereof, substantially as described.

4. An oil burner comprising a vertical rotatable air conduit open at the top, there being an opening in one side of said conduit and an outwardly extending vane to force air into and upwardly through said conduit; an oil vessel secured to said conduit adjacent the top thereof, said vessel having upwardly and outwardly flaring walls; means for introducing oil into said vessel; and a spreader head arranged above said oil vessel and extending laterally beyond the edges thereof, substantially as described.

5. An oil burner comprising a vertical cylindrical rotatable air conduit open at the top, there being an opening in one side of said conduit and an outwardly extending vane to force air into said opening and upwardly through said conduit; an oil vessel secured to said conduit adjacent the top thereof, said vessel having upwardly and outwardly flaring walls and said conduit projecting upwardly into said vessel; means for introducing oil into said vessel; and a spreader head arranged above said oil vessel and extending laterally beyond the edges thereof, substantially as described.

In testimony whereof I have signed my name to this specification.

CHARLES I. HOAG.
